UNITED STATES PATENT OFFICE.

BURL A. REYNOLDS, OF TOPEKA, KANSAS.

OIL BURNER.

Application filed May 22, 1922. Serial No. 563,184.

To all whom it may concern:

Be it known that I, BURL A. REYNOLDS, a citizen of the United States, residing at Topeka, in the county of Shawnee and State of Kansas, have invented new and useful Improvements in Oil Burners, of which the following is a specification.

The object of my said invention is to provide an easily disassembled and cleaned oil burner of high efficiency in use of various kinds of fuel oil and one that is susceptible of adjustment in such manner as to produce the best results in actual practice.

To the attainment of the foregoing, the invention consists in the improvement as hereinafter described and definitely claimed.

In the accompanying drawings, forming part of this specification:

Figure 1 is a diametrical section showing my novel oil burner as properly positioned in a stove.

Figure 2 is a top plan view of the burner per se.

Figure 3 is a horizontal section taken in the plane indicated by the line 3—3 of Figure 1, looking downwardly.

Figure 4 is a horizontal section taken in the same plane, looking upwardly.

Figure 5 is an enlarged detail top plan view of the oil retaining member of the burner.

Similar numerals of reference designate corresponding parts in all of the views of the drawings.

In Figure 1 a stove or fire box is designated by 1, and in furtherance of my invention the oil bowl 2 is fixed by fire clay 3 or other appropriate means in the stove. The said bowl 3 is of annular form, and in its center is a vertical passage 4, the wall 5 of which is extended about the proportional distance illustrated above the outer wall of the bowl.

Appropriately fixed as by screws 6 to the bottom of the bowl 2 is a cross-bar 7, apertured as indicated by 8 in Figure 3, and equipped with an upstanding sleeve 9, said sleeve 9 being integral with or fixed to the cross bar 7. At the underside of the cross bar 7 is a strap 10 spaced therefrom, and between the cross bar 7 and the strap 10 is maintained a nut 11 having a rim flange 12 which is knurled as illustrated so that it can be readily turned by hand. The sleeve 9 serves merely as a guide for a fuel supply pipe 13, the said pipe 13 being

threaded through the nut 11, and being provided at 14 with a nut, and being threaded from a point below the nut 11 to its upper end as clearly shown in Figure 1. From 60 this it follows that vertical movement of the pipe 13 will attend rotation of the nut 11.

In addition to the elements enumerated my improved burner comprises a dome 15, an oil retaining member 16, within the dome 15, and a diaphragm 17 within the lower portion of the member 16. The oil retaining member 16 is of general dome configuration, and is provided at 18 with a threaded aperture to receive the upper end 70 of the pipe 13. Surrounding the aperture 18 and extending upwardly from the top of the member 16 is a tubular projection 19 which serves to support the dome 15 in spaced relation to the member 16 and it is 75 notched at 20 so as to permit the radial passage of oil from the member 16 to the space between said member 16 and the dome 15. As shown in Figures 1 and 5 the top of the member 16 is provided with a plurality of annular grooves 21 in which oil will be retained with a view to assuring the oil being highly heated before it reaches the fire or oil in the bowl 2. The diaphragm 17 bears at its outer edge against the interior of the lower portion of the member 16 and serves merely to hold the lower portion of the member 16 in proper relation to the pipe 13. As best shown in Figure 1 the member 16 is provided at its lower end 90 with an outwardly flared and tapered straight flange 22, the lower edge of which rests in close proximity to or against the inner surface of the lower portion of the dome 15 with a view to promoting gravitation of oil between the lower portions of the dome 15 and the member 16. Said edge is notched as indicated by 23 in Figures 4 and 5. The before mentioned grooves 21 are preferable but not essential. I, 100 therefore, do not confine myself to the same.

The pipe 13 as before indicated is adjustable vertically through the medium of the nut 11, and therefore it is to be understood that an appropriate flexible conduit connection is to be interposed between the lower portion of the pipe 13 and a source of fuel oil supply.

In the practical operation of my novel burner the pipe 13 is adjusted vertically to 110 position the dome 15 and the member 16 relative to the upper edge of the bowl wall

5 with a view to regulating the passage of air from the central passage 4 of the bowl into the annular portion of the bowl. The air being deflected by the member 16 down upon the oil in the bowl or down into the fire with a view to thoroughly promoting the combustion.

In addition to the practical advantages ascribed to my improved burner it will be noted that all of the parts thereof may be readily disassembled, and consequently the burner may be quickly and thoroughly cleaned after which the parts may be as readily assembled for use.

15 I have entered into a detailed description of the construction and relative arrangement of the parts embraced in the present and preferred embodiment of my invention in order to impart a full, clear and exact 20 understanding of the said embodiment. I do not desire, however, to be understood as confining myself to the said specific construction and relative arrangement of parts inasmuch as in the future practice of the 25 invention various changes and modifications may be made such as fall within the scope of my invention as defined in my appended claims.

Having described my invention, what I 30 claim and desire to secure by Letters-Patent, is:—

1. In an oil-burner, the combination of an annular bowl with a central vertical passage therethrough, a fuel supply pipe extending upwardly through said passage and

above the bowl, a dome overhanging the central portion of the bowl, and a dome shaped interior member supported on the pipe and supporting the dome and spaced from the dome and having its lower edge 40 arranged to cooperate with the lower portion of the dome in affording means for the downward passage of fuel; the said dome shaped interior member having a tubular and notched upwardly extending projection 45 communicating with the pipe and also having annular grooves in its top about the said tubular projection.

2. In an oil burner, the combination of an annular bowl with a central vertical 50 passage therethrough, a fuel supply pipe extending upwardly through said passage and above the bowl, a dome overhanging the central portion of the bowl, and a dome shaped interior member supported on the 55 pipe and supporting the dome and spaced from the dome and having its lower edge arranged to cooperate with the lower portion of the dome in affording means for the downward passage of fuel; the said pipe being threaded and equipped to support the interior dome shaped member, and being associated with a cross bar apertured for the passage of the pipe, supporting means spaced below the bar, and a nut interposed 60 between the bar and said supporting means and receiving and engaging the threaded portion of the pipe.

In testimony whereof I affix my signature.

BURL A. REYNOLDS.
